UNITED STATES PATENT OFFICE.

WILLIAM B. HODGE, OF CHARLOTTE, NORTH CAROLINA, ASSIGNOR, BY MESNE ASSIGNMENTS, TO PARKS-CRAMER COMPANY, OF FITCHBURG, MASSACHUSETTS, A CORPORATION OF MASSACHUSETTS.

HUMIDIFYING APPARATUS.

1,284,337.

Specification of Letters Patent. Patented Nov. 12, 1918.

Application filed March 21, 1916. Serial No. 85,616.

To all whom it may concern:

Be it known that I, WILLIAM B. HODGE, (whose post-office address is Court House Square,) a citizen of the United States, residing at Charlotte, in the county of Mecklenberg and State of North Carolina, have invented certain new and useful Improvements in Humidifying Apparatus; and I do hereby declare the following to be a full, clear, and exact description of the invention, such as will enable others skilled in the art to which it appertains to make and use the same.

The invention relates to improvements in humidifiers, and more particularly to an atomizer type of the same, wherein water is sprayed or atomized into a room under pressure, from a compressed air supply, for the conditioning of the atmosphere to any desired degree of humidity.

It is well known that with the usual atomizer type of humidifier, the area of distribution is limited by the amount of air pressure, and, at the best, the water spray produced is only distributed over a comparatively small area from the orifice, of the spray nozzles, and only in one direction. Furthermore, the absence of "wetting down" depends upon the ability of the air to evaporate the free moisture as it issues from the atomizer, and if the drops of water do not come in contact with a sufficient amount of air to entirely evaporate them, they fall upon the machinery, floor or other bodies above which they are placed, and soon wet the surfaces, with corresponding deleterious effects.

The primary object of the invention is to provide an apparatus of the character mentioned, and one of a greater capacity, than that of the heretofore known types of the same, and so arranged as to prevent certain grave objections, obtaining in such known types, particularly in rooms having relatively low studded ceilings, or where there are no air drafts to aid in the proper distribution of the atomized spray of water.

A further object of the invention is to provide an apparatus of this character with means, whereby to secure a unit of high evaporative capacity, and relatively wide area of distribution, without the usual at-

tendant ill effects of "wetting down" the surfaces of the room, or of the machinery and other content of the same.

The general construction and arrangement 55 of the apparatus, as contemplated in the present invention, provides for the ejective effect of the atomizer head, or of the atomizer nozzles carried thereby, being supplemented with an air current of relatively 60 high velocity, the latter being produced either by a fan attached to each individual equipment or unit, or from a central station fan supplying a number of units. Each of 65 the units, aforesaid, comprises a casing having a plurality of outlets opening through a wall thereof, the latter being preferably semi-circular in conformation, and a corresponding number of atomizer nozzles, one 70 centered within each of said outlets and arranged to discharge outwardly therefrom, and, by provision of suitable curved deflecting surfaces, the supplemental air supply, admitted centrally of the rear of the casing, is properly and evenly proportioned to each 75 outlet and forcibly flows through the latter past the atomizer nozzles, thereby mixing with the atomized water spray a greatly increased amount of air, whereby the natural evaporation of the spray is greatly enhanced 80 and the area of distribution is proportionately increased.

With the foregoing and other objects in view, the invention resides in the certain new and useful construction and arrangement of parts as will be hereinafter more fully described, set forth in the appended claims, and illustrated in the accompanying drawings, in which,

Figure 1 is a top plan view of a preferred 90 form thereof,

Fig. 2 is a side elevation,

Fig. 3 is a rear elevation,

Fig. 4 is a longitudinal section on the line 95 2—2 of Fig. 2,

Fig. 5 is a top plan view of a modified form of the same, and,

Fig. 6 is a side elevation of the latter.

Referring to the drawings, in which similar characters of reference designate corresponding parts in the several views thereof, and more particularly to Figs. 1 to 4, inclu-

sive, thereof, wherein is illustrated a humidifying head embodying an individual means for supplying thereto a supplemental air supply for the proper evaporation and distribution of the water spray discharged therefrom into the room.

The humidifying head, in this instance, comprises a casing formed to provide a substantially semi-circular distributing portion 10, and a rearwardly disposed air intake portion 11, the latter being preferably cylindrical in form, and having a diameter substantially less than the width of the former, as shown. Opening through the forward or semi-circular wall 12, of the distributing portion 10, are a plurality of outlets 13, preferably rectangular in cross-section and of even width throughout their depth within the casing, through which is to be discharged a supplemental or distributing volume of air supplied thereto from the air intake portion 11. This supplemental or distributing supply of air is properly proportioned to, or equalized between, each outlet 13 by means of suitably curved, or otherwise arranged, deflecting partitions or vanes 14, which provide channels connecting the air intake portion 11, with the outlets 13, for the purpose.

Adjacent the outer end of each of the outlets 13, and centered therein with respect to the walls of the same, is arranged, for outward distribution therefrom, an atomizer head 15, of any desired or suitable construction, upon which is impressed, in a downward direction, preferably, through the medium of a pipe connection 16, a supply of compressed air from a distributing main or pipe 17, the latter being curved over the top wall of the casing in conformity with the curvature of the wall 12, of the casing, and connected at one end to a suitable source of supply, and having its other end closed in any suitable manner, as shown.

The impressing of the air supply, aforesaid, on the atomizer heads 15, creates a suction action which lifts water through pipe connections 18 from a supply main 19, and sprays the same outwardly of the casing, from the nozzles of the heads, in a diffused manner. This water supply main 19 may be connected with an independent supply, or to a conduit common to a plurality of the humidifying apparatus, and in either case, a predetermined level of water is to be maintained in the pipe, or pipes, 19 by means of a float valve 20, or other similar device, or, in certain preferred cases, a small water tank 21, with a float controlled valve 20 therein, may be directly attached to the casing, in which instance, the main water supply, not shown, is to be connected to the valved outlet 22, of the tank. This latter arrangement is especially useful where only one or two equipments of this kind are to be installed, or where it is desired to keep

the room as free as possible from an otherwise excessive amount of piping.

Engaged over the rear edge of the cylindrical air intake portion 11, of the casing, is a split ring-like frame 23, having spaced lugs 24, rising from its opposed ends, and adapted to support a shaft or bolt member 25 from which is suspended a motor 26, the latter being of any desired type and carried by a frame 27 having lugs 28, engaged by the shaft or bolt member 25. This method of mounting the motor 26 admits of its being swung outward from its normally operative position, the same being partially within the casing and concentric with the walls thereof, for the purpose of giving ready access to the interior of the casing and for the cleaning out of the latter, the cleaning of the motor and the lubrication of its parts, as is necessary from time to time. The motor 26 is provided with fan blades 29, which are so arranged as to draw air from the outside of the casing and force the same, in any desired degree of velocity, through the intake portion 11 and through the channels between the deflecting partitions or vanes 14 to the outlets, as hereinbefore mentioned.

In this type of humidifying apparatus, with the atomizer heads disposed, preferably, radially of the casing, as shown, each in its respective supplemental air channel, and when in operation, the primary or compressed air supply tends to throw a spray of finely atomized water from each of the various jets outward of the casing, covering an arc of approximately 180°, more or less, depending upon the number of outlets desired, and the arc of distribution necessary for the proper conditioning of the atmosphere of the room.

As heretofore stated, in the known types of humidifying apparatus, the jet of air used for the purpose of atomizing the water is not sufficient to force the finely attenuated spray to any appreciable distance from the point of discharge, but by impressing a supplemental supply of air, of relatively high velocity, back of the atomizer nozzles to produce a strong draft over and around each of the latter, it is to be readily observed that a far more adequate amount of air is brought into immediate contact with each spray, so that it is not only carried to a comparative great distance beyond the normal area of distribution, but, along with such increased travel, the added amount of air assists in a more rapid evaporation of the moisture, and puts it in a gaseous state, whereby it becomes available in its desired humidifying effect, and, by reason of the provision of the deflecting partitions or vanes, before mentioned, the supplemental supply of air is equally proportioned to the several atomizer heads, through their respective channels, so that the entire distribu-

tion of moisture is maintained uniform throughout the area to be conditioned by each unit of the apparatus.

Similarly, in Figs. 5 and 6 of the drawing, the same type of apparatus is illustrated, but is more especially designed for use in connection with a central station system (not shown), wherein an air supply is distributed to various parts of a building through the medium of flues, or the like, such as is designated at 30. It is well known that in this type of system, especially in the winter months, a blast of hot, extremely dry air is forced into rooms and interiors for the purpose of heating, and many improvements have been suggested for moistening this air supply, at the central station, prior to its being impelled into the flues by the usual driving or suction fans, but this has only been accomplished at a great and unwarranted expense, and in the utilization of an excessive amount of space for the proper positioning of an air washing apparatus suitably proportioned for the purpose.

In this latter type of apparatus, the individual motor unit, and its supporting frame, is dispensed with, and the air intake portion 31 of the casing, is, preferably, modified to provide a substantially rectangular opening to conform to the usual similarly shaped opening of the flue 30, and the compressed air supply pipe 32, and the water supply pipe 33 are led into the intake portion 31, and connect to distributing heads 34 and 35, respectively. Radiating from the air distributing head 34 are a plurality of branch air pipes 36, and from the water distributing head 35, a plurality of branch water pipes 37, each arranged in pairs, corresponding in number to that of the atomizer nozzles 38, of the unit, and connecting the latter in the manner of the before-mentioned construction. The distributor heads 34 and 35 may be conveniently supported in spaced relation within the casing in any desired manner, or, as shown, by means of a spacing sleeve or pipe section 39, interposed between the heads, and a tie rod 40, passed through the sleeve, and secured, at its opposite ends, to the heads in any suitable manner, or by the nuts 41, as shown.

The equipment, thus provided, lends itself admirably to the purpose mentioned, as it can be attached directly to the flue outlet, opening through the wall of the room or building in which it is to be used, and the air, produced by the central station fan, has the same effect, so far as the distribution and evaporation of the atomized moisture is concerned, and it is readily understood that this convenient, efficient, as well as simple means of moistening the normally dry, hot blast of air, aforesaid, is an extremely advantageous form of humidifying or conditioning such incoming supply of the air,

not only rendering it less injurious to health, but also more adaptable to many kinds of manufacturing operations, where humidity plays any appreciable part therein.

In the last mentioned type of the apparatus, it is to be desired that provision be made for ready access to the interior of the intake portion 31, of the casing, particularly so, for the cleaning away of any lint or other waste matter which tends to accumulate around the distributor heads, and branch pipe connections leading therefrom, and to this end, there is provided a handhole 43, opening through the top wall of the portion 31, immediately above the upper distributor head 34, and which is adapted to be closed by a cover 44 slidably mounted in guideways 45, extending across the top wall, aforesaid, for the purpose.

Either type of these apparatus may be supported in operative position by means of any suitable or desired form of hangers, such as, for instance, the strap hangers 42, as shown, or in any other manner as conditions may require.

It is readily evident that the exact form of construction of the invention, as shown and described herein, is not necessarily required for the accomplishment of the desired effect, as the apparatus may be made in an entirely circular form, with the fan motor supported concentrically of the top wall of the casing thereof, and the deflecting partitions or vanes so arranged that the forced draft, of the supplemental air supply, distributes radially past all of the atomizers disposed along an arc of 360°, and similarly, other forms, which would readily suggest themselves to one skilled in the art, may be resorted to without departing from the spirit of the said invention.

Having thus fully described the invention, what is claimed is:—

1. Radially disposed outwardly discharging multiple means for producing a finely divided water spray, in combination with means for producing an increased area of distribution of the latter.

2. Outwardly discharging multiple means for producing a finely divided water spray, in combination with means for producing an auxiliary draft of air, and deflecting the same, whereby said auxiliary draft of air is proportionately distributed across said multiple means.

3. A series of outwardly discharging atomizers with air and water supply pipes, means for supplying a constant water level in said water supply pipe, and means for creating and forcing an additional current of air across said atomizers, whereby the evaporation and distribution of the spray produced by said atomizers is increased.

4. A series of atomizers, each with its respective compressed air and water supply,

an air passageway surrounding each atomizer duct, means for creating and forcing an additional current of air, and means for subdividing said current of air, whereby each 5 atomizer receives through said vaporizers any desired proportion of said current of air.

5. In an apparatus of the class described, the combination of an outwardly discharging series of devices for producing an attenuated water spray, and means for producing an additional current of air for distributing the spray over a comparative wide area.

10 6. In an apparatus of the class described, the combination of an outwardly discharging series of atomizers for producing an attenuated water spray, and means for producing an additional current of air to distribute 20 the spray over a comparative wide area.

7. In an apparatus of the class described, the combination of a series of atomizers disposed along a predetermined arc for producing an attenuated water spray, and means for distributing the spray over a comparative wide area.

30 8. In an apparatus of the class described, the combination with a casing, of a series of atomizers disposed within said casing and arranged to discharge outwardly therefrom, and means for distributing the water spray, from said atomizers, over a comparatively wide area.

35 9. In an apparatus of the class described, the combination with a casing, of a series of atomizers disposed along an arc within said casing and arranged to discharge outwardly therefrom, and means for distributing the water spray, from said atomizers, over a 40 comparative wide area.

45 10. In an apparatus of the class described, the combination with a casing, of a series of atomizers disposed along an arc within said casing and arranged to discharge outwardly therefrom, and means for supplying a current of air to the rear of said atomizers, whereby the normal area of distribution of the water spray, from the latter, is greatly increased.

50 11. In an apparatus of the class described, the combination with a casing having a plurality of outlets opening through a wall thereof, an atomizer disposed within each of said outlets and discharging outwardly therefrom, and means for supplying a current of air to the rear of said atomizers, whereby the normal area of distribution of the water spray, from the latter, is greatly increased.

60 12. In an apparatus of the class described, the combination with a semi-circular casing having a plurality of outlets opening through the curved wall thereof, an atomizer disposed within each of said outlets and dis- 65 charging outwardly therefrom, and means

for supplying a current of air to the rear of said atomizers, whereby the normal area of distribution of the water spray, from the latter, is greatly increased.

13. In an apparatus of the class described, the combination with a semi-circular casing having a plurality of outlets opening through the curved wall thereof, an atomizer disposed within each of said outlets and discharging outwardly therefrom, a water supply for said atomizers, a compressed air supply for ejecting the water from said atomizers, and means for supplying a current of air to the rear of said atomizers, whereby the normal area of distribution of the water spray, from the latter, is greatly increased.

14. In an apparatus of the class described, the combination with a semi-circular casing having a plurality of outlets opening through the curved wall thereof, an atomizer disposed within each of said outlets and discharging outwardly therefrom, deflecting partitions disposed within said casing and forming channels each connecting with respective outlets, and means for supplying a current of air through said channels to the rear of said atomizers, whereby the normal area of distribution of the water spray, from the latter, is greatly increased.

15. In an apparatus of the class described, the combination with a semi-circular casing having a plurality of outlets opening through the curved wall thereof, an atomizer disposed within each of said outlets and discharging outwardly therefrom, an intake 100 casing disposed to the rear of said semi-circular casing, deflecting partitions disposed within said casing and forming channels each connecting their respective outlets with said intake casing, and means for supplying a current of air through said intake casing 105 and said channels to and around said atomizers, whereby the normal area of distribution of the water spray, from the latter, is greatly increased.

110 16. In an apparatus of the class described, the combination with a semi-circular casing having a plurality of outlets opening through the curved wall thereof, an atomizer disposed within each of said outlets and discharging outwardly therefrom, an air 115 intake casing disposed to the rear of said semi-circular casing, deflecting partitions disposed within said casing and forming channels each connecting their respective outlets with said intake casing, said deflecting partitions being arranged to proportion the air from said intake casing equally to each of said channels, and means for supplying a current of air through said intake 120 casing and said channels to and around said atomizers, whereby the normal area of distribution of the water spray, from the latter, is greatly increased.

17. In an apparatus of the class described, 130

- the combination with a semi-circular casing having a plurality of outlets opening through the curved wall thereof, an atomizer disposed within each of said outlets 5 and discharging outwardly therefrom, a water supply for said atomizers, a compressed air supply acting upon said atomizers in a manner to discharge therefrom the water in the form of a finely divided 10 spray, and means for supplying a current of air to the rear of said atomizers, whereby the normal area of distribution of the water spray is greatly increased.
18. In an apparatus of the class described, 15 the combination with a semi-circular casing having a plurality of outlets opening through the curved wall thereof, an atomizer disposed within each of said outlets and discharging outwardly therefrom, a 20 water supply pipe common to all of said atomizers, means for maintaining a predetermined water level in said supply pipe, a compressed air supply also common to all 25 of said atomizers and acting upon the latter in a manner to discharge therefrom the water in the form of a finely divided spray, and means for supplying a current of air to the rear of said atomizers, whereby the 30 normal area of distribution of the water spray is greatly increased.
19. In an apparatus of the class described, 35 the combination with a semi-circular casing having a plurality of outlets opening through the curved wall thereof, an atomizer disposed within each of said outlets
- and discharging outwardly therefrom, an intake casing disposed to the rear of said semi-circular casing, a water supply for said atomizers, a compressed air supply for ejecting the water from said atomizers in the 40 form of a finely divided spray, and a fan motor disposed within said intake casing for driving a current of air through said semi-circular casing and around said atomizers, whereby the normal area of distribution 45 of the water spray is greatly increased.
20. In an apparatus of the class described, 50 the combination with a semi-circular casing having a plurality of outlets opening through the curved wall thereof, an atomizer disposed within each of said outlets and discharging outwardly therefrom, an intake casing disposed to the rear of said semi-circular casing, a water supply for said atomizers, a compressed air supply for ejecting the water from said atomizers in the 55 form of a finely divided spray, and a fan motor removably supported within said intake casing for driving a current of air through said semi-circular casing and 60 around said atomizers, whereby the normal area of distribution of the water spray is greatly increased.

In testimony whereof I affix my signature in presence of two witnesses.

WILLIAM B. HODGE.
